JEWELRY BOX

Philip Beck, New York, N.Y., assignor to Bulova Watch Company, Inc., Flushing, N.Y., a corporation of New York

Filed Sept. 12, 1968, Ser. No. 13,519

Term of patent 7 years

Int. Cl. D9—04

U.S. Cl. D9—231

FIG. 1

FIG. 3

FIG. 2

FIG. 4

FIG. 5

FIG. 1 is a front perspective view of a jewelry box, showing my new design;

FIG. 2 is a perspective view similar to FIG. 1 showing the jewelry box in open condition;

FIG. 3 is a rear view thereof;

FIG. 4 is a side view thereof;

FIG. 5 is a bottom view thereof.

I claim:

The ornamental design for a jewelry box, as shown.
